UNITED STATES PATENT OFFICE.

VILHELM ÖHRSTRÖM, OF STOCKHOLM, SWEDEN, ASSIGNOR TO AKTIEBOLAGET LAURIN & PERKEL, OF STOCKHOLM, SWEDEN, A FIRM.

PERMUTATION-PADLOCK.

1,375,603.

Specification of Letters Patent. Patented Apr. 19, 1921.

Application filed September 23, 1920. Serial No. 412,346.

To all whom it may concern:

Be it known that I, VILHELM ÖHRSTRÖM, a subject of the King of Sweden, and a resident of Stockholm, Sweden, have invented certain new and useful Improvements in Permutation-Padlocks, of which the following is a specification.

This invention relates to improvements in permutation padlocks in which the shackle 10 is held by a spring-actuated bolt, which is brought into and out of engagement with the shackle by locking disks of special shape connected with tumblers partly projecting from the lock-plate and provided 15 with figures or other signs on their circumference.

In the accompanying drawings I have illustrated one way of carrying out the invention, in which:

20 Figure 1 is a vertical section through the lock embodying the present invention;
Fig. 2 is a side elevation of the same;
Fig. 3 is a top plan view;
Fig. 4 is a front elevation of one of the 25 tumblers;
Fig. 5 is a side elevation of the same;
Fig. 6 is a top plan view of Fig. 4;
Fig. 7 is a plan view of the locking bolt; and

30 Fig. 8 is a side elevation of the same.
Referring now more particularly to the drawings, wherein like and corresponding parts are designated by similar reference numerals throughout the several figures, I 35 have illustrated the lock which consists of a casing having supported therein a vertical central shaft 2. Loosely mounted and arranged in superimposed relation is a plurality of tumblers or disks 1. These tumblers are flexibly supported upon the shaft 2 by means of coil springs 2', as is illustrated in Fig. 1. Slidably supported within the lock casing is a shackle 7 having substantially a U-shaped configuration and 40 one arm 7' of this shackle is greater in length than the arm 7'' thereof, but both arms are adapted to project within the lock casing when the shackle is in locked position. These tumblers 1 each have formed 45 one face thereof a segmental locking disk 3 which is cut away as at 4. A slideable locking bolt 5 is also arranged within the lock casing having formed with one end thereof an upwardly projecting portion

55 terminating in a hook 6, which hook is adapted to engage a slot formed within the arm 7' of the shackle, whereas the opposite end of this bolt 5 is adapted to engage a recess formed within the arm 7'' of the shackle whereby the latter will be retained 60 in locked position. This bolt 5 is provided with an elongated slot or recess 5' for the reception of the bolt 2 and this bolt 5 is arranged between the tumblers so as to divide the tumblers in pairs, as is better 65 illustrated in Fig. 1. These tumblers are so arranged upon the shaft 2 that the disks 3 will lie closely adjacent, and adapted to ride upon the peripheries of these locking disks 3 are the outer ends of the arms 9, 70 which latter are carried by the bolt 5. A spring 8 engages the bolt 5 for normally holding the arms 9 against the circumference of the locking disks 3 and normally tends to hold this bolt 5 out of engagement 75 with the arms 7' and 7'' of the shackle 7.

When all the locking disks or any of them assumes such a position that any of the arms 9 rests against the rounded portion of the circumference of the disk or 80 disks, the hook 6 is held in engagement with the slot in the shackle 7. After the tumblers 1 have been turned into such positions that all of the arms 9 rest against the rectilinear portions 4 of the disks, the bolt 85 5 has been forced by the spring 8 out of engagement with the shackle, which is consequently released, so that it may be drawn out of the lock. When the lock is again to be locked, the shackle is pushed into the 90 lock and one or more of the tumblers 1 are turned, so that the arms 9 are pressed back by the rounded portions of the disks 3, whereby the hook 6 is again brought into engagement with the slot in the shackle. 95

This arrangement of the lock allows of a great many combinations of the mutual positions of the locking disks, only one of these combinations releasing the bolt and shackle. 100

Only two pairs of tumblers and two arms 9 are shown in the drawing. Nothing prevents, however, the arrangement of more pairs of tumblers with their appertaining disks 3 and of a corresponding number of 105 arms 9.

Having now particularly described the nature of this invention and in what man-

ner the same is to be performed, what I claim as new and desire to secure by Letters Patent is:—

1. A permutation lock comprising a casing, a U-shaped shackle having its opposite ends projecting within said casing, a central shaft, a plurality of tumblers arranged in pairs and flexibly supported upon said shaft, a segmental disk 10 formed with one face of each tumbler, a locking bolt arranged between each pair of tumblers, arms projecting from said locking bolt and adapted to rest against the peripheries of said segmental disks, a spring 15 for holding said locking bolt in one position, and said disks adapted to hold said locking bolt into engagement with the opposite ends of said shackle, substantially as and for the purpose specified.
- 20 2. A permutation lock comprising a casing, a shackle adapted to be locked within said casing, a shaft supported within said casing, a plurality of tumblers mounted upon said shaft and arranged in pairs, a locking bolt arranged between each pair of tumblers, a hook carried by said locking bolt, said tumblers being adapted to hold said hook in locking engagement with said shackle, and means for normally holding 25 said hook out of locking engagement with said shackle when said tumblers are released.
- 30 3. A permutation lock comprising a casing, a central shaft arranged therein, a plurality of horizontally arranged tumblers 35

flexibly supported upon said shaft, a segmental disk carried by each tumbler, a locking bolt slidably arranged within said casing, arms carried by said locking bolt and adapted to engage the peripheries of said 40 disks, a shackle adapted to be inserted within said casing and said locking bolt being adapted to be held in locking engagement with said shackle by means of said disks substantially as and for the purpose 45 specified.

4. A permutation lock comprising a casing, a shackle having its opposite ends projecting within said casing, a vertical central shaft arranged within said casing, a 50 plurality of circular tumblers loosely mounted upon said shaft and partly projecting from one face of said casing, a segmental disk formed with one face of each tumbler, said tumblers being arranged in 55 pairs whereby the segmental disks of each pair will face one another, a locking bolt arranged between each pair of tumblers and adapted to engage the outer peripheral faces of said segmental disks, means for 60 normally holding said locking bolt out of engagement with said shackle, and said tumblers being adapted to be turned whereby the segmental disks carried thereby may retain the locking bolt into locking engagement with said shackle. 65

In witness whereof I have hereunto set my hand.

VILHELM ÖHRSTRÖM.
